US0D1037960S

(12) **United States Design Patent** (10) **Patent No.:** **US D1,037,960 S**
(45) **Date of Patent:** **** Aug. 6, 2024**

(54) **VEHICLE DOOR PANEL**

(71) Applicants: **Zhejiang ZEEKR Automobile Research & Development Co., Ltd., Ningbo (CN); Zhejiang Geely Holding Group Co., Ltd., Hangzhou (CN)**

(72) Inventor: **Emilie Sicot, Gothenburg (SE)**

(73) Assignees: **ZHEJIANG GEELY HOLDING GROUP CO., LTD., Hangzhou (CN); ZHEJIANG ZEEKR AUTOMOBILE RESEARCH & DEV. CO., LTD, Ningbo (CN)**

(**) Term: **15 Years**

(21) Appl. No.: **29/834,790**

(22) Filed: **Apr. 14, 2022**

(51) LOC (14) Cl. **12-08**

(52) U.S. Cl. **D12/195**
USPC .....
